HANDWHEEL FOR LOOMS

Joseph M. Patrick, Worcester, Mass., assignor to
Crompton & Knowles Loom Works, Worcester,
Mass., a corporation of Massachusetts

Application August 23, 1944, Serial No. 550,827

2 Claims. (Cl. 287—53)

This invention relates to improvements in hand wheels for looms and it is the general object of the invention to provide a simple hand wheel which can be readily assembled on a loom shaft and held tightly in position.

A loom is occasionally stopped by one or another of its stop motions, such as the weft or warp stop motion, or the protector mechanism, in which event it is usually desirable to turn the loom backwardly by manual means. Hand wheels for this general purpose have been utilized heretofore, but they have generally been expensive to make and of such weight that their momentum of rotation increases the difficulty of stopping the loom. It is an important object of my present invention to provide a light weight hand wheel amply strong to withstand the strains incident to manual turning of the loom but at the same time light enough so that it adds very little to the force which must be overcome when the loom is stopped.

It is a further object of my present invention to provide a hand wheel formed of a thin sheet metal web the outer part of which is secured to a hand rim or ring and the inner part of which is provided with clamping means near the center of rotation. The clamping means may include holding and checking collars between which the web is tightly clamped.

It is another object of my present invention to provide a hand wheel having a hub made of two parts one of which has the aforesaid web mounted thereon and the other part of which may be threaded to the first part or secured thereto in other suitable manner. After the two parts of the hub have been secured together in clamping relation with respect to the web they are slotted for the reception of a key. When assembled on the shaft the key serves to prevent relative angular movement of the two parts of the hub and the latter therefore maintain their tight clamping relationship with the web of the wheel.

Hand wheels are not always necessarily applied to a shaft immediately after their manufacture and during the interval between the time of their making and the time of their use relative movement of the two hub forming parts may occur. By reason of the aforesaid key slot, however, it will be necessary to return the two parts of the hub to their original clamping position before the wheel can be assembled on the shaft.

With these and other objects in view which will appear as the description proceeds, my in-

vention resides in the combination and arrangement of parts hereinafter described and set forth.

In the accompanying drawing, wherein a convenient embodiment of my invention is set forth.

5. Fig. 1 is a front elevation of my improved hand wheel together with the shaft on which it is mounted and the adjacent part of a loom frame, Fig. 2 is a side elevation looking in the direction of arrow 2, Fig. 1.

10. Fig. 3 is a side elevation of the wheel web and ring with the hub parts and shaft removed.

Fig. 4 is an enlarged fragmentary view showing the manner in which the web is secured to the ring.

15. Fig. 5 is a group view in which the three parts of the hand wheel are shown detached preparatory to assembly.

Fig. 6 is an enlarged vertical section on line 6—6 of Fig. 2, the shaft being indicated in dot and 20 dash lines so that the key slot may be shown in full-lines.

Fig. 7 is a vertical transverse section on line 7—7 of Fig. 6, and

Fig. 8 is a plan view of the holding collar. 25 In Fig. 1 I have shown a loom frame 10 and one of its shafts 11, this shaft usually being the upper or crank shaft of the loom. The frame supports a bearing 12 in which the shaft rotates and from which it projects laterally from the loom as at 13. The hand wheel designated generally at H is secured to the shaft at a point spaced from the loom frame and adjacent parts so that the shaft 11 may be turned manually to effect either forward or reverse movement of the 30 loom.

35. The hand wheel H forming the subject matter of my present invention comprises a web 15 which may be made of thin sheet metal, such as steel, and as indicated in Fig. 2 is provided with

40. four radial flat arms 16. A ring or rim 17 may be made of a hollow metal tube such as steel, as indicated in Fig. 4, and its inner wall is provided with slots 18, one for each of the arms 16. The latter extend into their respective slots and may

45. be held in position as by welding indicated at 19. The center of the web 15 is provided with a non-circular opening 20 which has arcuate sides 21 formed concentric with the axis of the wheel, and top and bottom straight edges 22 and 23 which are preferably parallel. Any other suitable form of non-circular opening 20 may be utilized, but I find the form illustrated in Fig. 3 to be convenient.

50. The wheel is provided with two hub members one of which is a holding collar 25 and the other

55. 26 which is a hub member.

of which is a checking nut, collar, or the like 26. The holding collar or member preferably has a circular periphery and is provided with a bore 27 for the reception of the shaft 11. As viewed in Fig. 6 a reduced projection 28 extends from the left of the main body 29 of the holding collar and forms with the latter a shoulder 30 lying in a plane perpendicular to the axis of the shaft and positioned for engagement with the right surface 31 of the web 15 as view in Fig. 6. The projection 28 is generally of a form to fit snugly into the opening 20 of the web and has side screw threads 32. The top and bottom of the projection 28 are slabbed, respectively, at 33 and 34 to fit the edges 22 and 23 of the opening 20. The projection 28 is thus formed with screw threads on its sides and flat surfaces on its top and bottom.

The checking collar or nut 26 is provided with a flat web 40 and a circular flange 41 having internal screw threads 42 to fit the screw threads 32 of the holding collar. The flange and web 40 form a cavity 43 to receive the projection 28. The checking member is provided with a bore 45 extending through web 40 to receive the shaft 11, and the screw threads 32 and 42 are concentric with the axis of the hand wheel and of their respective members 25 and 26.

When assembling the hand wheel the holding collar 25 may be moved to the left as viewed in Fig. 5 until the projection 28 has been inserted through the opening 20 with the shoulder 30 in engagement with the surface 31 of the web 15. The checking collar 26 is then moved to the right, Fig. 5, and threaded on the screw threads 32 until its surface 46 engages the left hand surface 47 of the web 15, as indicated in Fig. 6. The checking collar is threaded tightly in position so that the web is clamped firmly between the members 25 and 26. Up to this time in the process of making the hand wheel the bores 27 and 45 have been smooth and continuous, but after the three parts of the hand wheel, that is the web and the two hub forming members, are assembled in tight relationship, a key slot is cut in the bores of both of the members 25 and 26. In Fig. 6 that part of the key slot which is in the holding collar 25 is indicated at 50, while that part of the key slot in the checking collar is shown at 51. These two slots are in alignment to receive a key 52, see Fig. 7, which is also received by a slot 53 in the shaft 11.

After the key slots 50 and 51 have been cut the hand wheel is ready for application to the shaft 11, but it may be that some time will elapse between the manufacturing of the hand wheel and its application to the shaft. If during this time relative rotary motion should take place between the members 25 and 26 in a direction to loosen their clamping relationship with the web 15, the slots 50 and 51 will be out of register with each other. If under these conditions an attempt is made to apply the wheel to a shaft the inability of the key 52 to enter both of the slots 50 and 51 will indicate to the workman that the two parts 25 and 26 are not in their correct angular relationship and the latter can thereupon be reestablished. The slots 50 and 51 will then align and will receive the key 52. This reestablishment of correct angular relation of the hub forming parts to permit fitting of the key will return them to tight clamping position relatively to the web

15. The cavity 43 is deep enough measured axially of the checking member 26 to prevent the projection 28 from touching the web 40 when the parts are in tight holding relationship with respect to the web 15.

The tubular rim or ring 17 is shown herein as a convenient means for providing a light hand grip which will develop a minimum of momentum of rotation during running of the loom. So far as certain features of my invention are concerned, however, I do not wish to be limited to the construction set forth for instance in Fig. 4. The web is provided with recesses 60 which permit grasping of the rim 17 for purposes of turning the hand wheel manually.

From the foregoing it will be seen that I have provided a light weight hand wheel including a sheet metal web and hub forming members between which the web is clamped. The web is provided with a non-circular opening which fits a projection of like cross section on the holding collar 25, and screw threads on the projection provide means by which the checking collar 26 may be turned tightly against the web 15. The web 15 is therefore seen to be held against rotation with respect to the member 25 and when the latter is keyed to the shaft 11 the hand wheel and shaft turn together. Furthermore, it will be seen that the key 52 serves to prevent relative rotation of the parts 25 and 26 after they have been assembled on the shaft and assurance is thus given that the hand wheel will be kept tightly clamped in correct position so that it will turn in a plane perpendicular to the axis of the shaft 11. The two key slots 50 and 51 must be in alignment before the key 52 can be fitted and this condition requires that the two parts 25 and 26 be in their original tight clamping position with respect to the web 15 before the wheel can be completely assembled on the shaft.

Having thus described my invention it will be seen that changes and modifications may be made therein by those skilled in the art without departing from the spirit and scope of the invention and I do not wish to be limited to the details herein disclosed, but what I claim is:

1. In a hand wheel for a shaft having a key thereon, a flat thin web extending around the shaft, a holding member on the shaft having screw threads thereon, and a checking member threaded on the screw threads and clamping the web against the holding member, said members having aligned key slots receiving said key and the latter preventing relative angular movement of said members.

2. In a hand wheel for a shaft having a key thereon, a flat thin web having a hole therein formed with opposite straight edges connected by arcuate edges concentric with the shaft extending around the shaft, a holding member on the shaft, a projection extending from the member along the shaft and through the web, said projection having opposite flat surfaces engaging said straight edges and having rounded surfaces fitting around said arcuate edges, screw threads on said rounded surfaces of said projection, and a checking member threaded on said screw threads and clamping the web against said holding member, said members having aligned key slots receiving said key and the latter preventing relative angular motion of said members.

JOSEPH M. PATRICK.
